UNITED STATES PATENT OFFICE.

WILLIAM F. ROSENFIELD, OF WASHINGTON, DISTRICT OF COLUMBIA.

AIR VALVE.

Application filed June 19, 1928. Serial No. 286,682.

This invention relates to an auxiliary air valve.

An object of the invention is the provision of an air valve adapted to be connected with the intake manifold of an internal combustion engine and at a point between the engine and the throttle valve in the carburetor for admitting the proper quantity of auxiliary air to the mixture in accordance with the needs of the engine at varying speeds.

Another object of the invention is the provision of an auxiliary air supply device adapted to be connected at a point on the intake manifold which is between the usual throttle valve and the engine, and in which a valve is suspended out of engagement with a seat during the normal operation of the engine, the valve being drawn into the seat against the action of a spring when the throttle valve is closed, or substantially closed, for preventing an auxiliary air supply to the mixture at this time, the spring moving the valve away from its seat when the throttle valve is open and when the suction in the intake pipe is insufficient to overcome the action of the spring.

This invention will be best understood from a consideration of the following detailed description in connection with the accompanying drawings; nevertheless, it is to be understood that the invention is not confined to the disclosure being susceptible of such changes and modifications as shall define no material departure from the salient features of the invention as expressed in the appended claims.

In the drawings:—

Figure 1 is a side view in elevation of an engine showing my auxiliary air intake device attached to the usual intake pipe,

Figure 2 is a vertical section of the auxiliary air device taken along the line 2—2 of Fig. 3,

Figure 3 is a horizontal section taken along the line 3—3 of Fig. 2.

Referring more particularly to the drawings 10 designates an internal combustion engine which is supplied with a suitable mixture from a carburetor, not shown, and through an intake pipe 11. A throttle valve 12 is adapted to control the flow of mixture to the engine, in a manner which is well known.

The intake pipe 11 is provided with an opening 13 into which is threaded a nipple

14. A body 15 is threaded at 16 on the nipple 14 and has a central passage 17 for connecting a chamber 18 with the interior of the intake manifold 11. The body member has its interior wall provided with a plurality of ribs 60 19 provided with passages 20, one of the passages being in open communication with a horizontal passage 21. The passages 20 are substantially co-extensive in length with the height of the chamber 18.

A collar 22 fits snugly on the body member and has a port 23 adapted to be aligned with the passage 21 whereby atmospheric air may enter the passage 21 and circulate by means of the vertical passage 20 into chamber 18, 70 where it is drawn through the central passage 17 in a manner which will be presently explained. The collar 22 has a slot 24 which receives a bolt 25 threaded into the body member 15, for maintaining the collar in place 75 while limiting the movement of said collar.

A plug 30 has a reduced portion 31 threaded at 32 into the outer end of the hollow body 15. A shoulder 33 in the plug 30 engages the outer end of the body member 15 and aids in 80 sealing the chamber 18 at its outer end from the atmosphere.

A housing or sleeve 34 is provided with external threads 35 adapted to be screwed into the internal threads 36 of the plug 30. A nut 85 37 aids in securing the housing 34 in position in the plug. The inner end of housing is closed, as shown at 38, and is seated on the inner end of the plug 30, and is also engaged by a spring 39 located within the housing 34. 90 The outer end of the housing is closed by a cap nut 40.

A valve 45 is adapted to engage a seat 46 in the passage 17 and is supported by a stem 47 which is slidably mounted in passages 48 and 95 49 formed respectively in the plug 30 and the inner portion of the housing 34. This stem also is slidable in a passage 50 in the cap nut 40. A nut 51 is threaded on the stem 47 and engages the outer end of the spring 39.

The operation of my device is as follows: The spring 39 suspends the valve 45 by means of the nut 51 and the stem 47, and retains it in an inoperative position and in spaced relation with the seat 46 so that atmospheric air which enters the passage 21 and circulates through the passages 20 in the body member will enter the passage 17 and the intake manifold 11.

When the throttle valve 12 is closed or the same is approximately closed, the suction will 110

cause the ball valve 45 to be seated thereby cutting off auxiliary air to the intake manifold. As soon, however, as the throttle valve is open and the vacuum is broken in the intake manifold, the spring 39 will move the valve 45 from the seat 46 to permit auxiliary air to enter the intake manifold 11. The vertically disposed passages 20 are arranged around the ball valve 45 so that the air entering the vertically disposed passages adjacent the transverse passage 21 will pass around the bottom of the ball valve 45 in order that it will be easily distributed to the passage 17.

By rotating the threaded housing 34 after the releasing of the nut 37, the tension on the spring 39 may be varied in order to properly position the valve for its seating and for its release from its seat during variations in the suction produced in the intake manifold.

20 I claim:—

1. An auxiliary air intake valve comprising

a hollow body provided with an air inlet and a discharge port, a valve in the hollow body, a seat engaged by the valve when said valve is moved towards the discharge port for cutting off the flow of air through the body, a spring for retaining the valve normally unseated, a tubular member threaded into the body and housing the spring.

2. An auxiliary air intake valve comprising a hollow body provided with an air inlet and a discharge port, a valve in the hollow body, a seat engaged by the valve when said valve is moved towards the discharge port for cutting off the flow of air through the body, a spring for retaining the valve normally unseated, a tubular member threaded into the body and housing the spring, the tubular member being adjustably mounted in the body for varying the tension on the spring.

WILLIAM F. ROSENFIELD.
